UNITED STATES PATENT OFFICE

WILLIAM T. COX, OF OKLAHOMA CITY, OKLAHOMA

ADJUSTABLE UNIVERSAL POST TOP AND ARM

Application filed July 25, 1929. Serial No. 381,057.

My invention pertains to adjustable universal post top and arm and relates to fittings for tubular and solid fence posts of any suitable material.

The objects of my invention are to provide a device of this character for use in connection with the top of a fence post and a wire supporting steel arm adapted for adjusted positioning; which will be new, novel, and of utility; which will be strong, durable, cheap, and efficient in accomplishing the purposes for which it is intended; to provide a device in which one size and style of arm may be interchangeably used with varying sized casting tops; a device in which the interchangeable arm may be positioned in the same vertical plane as that of the wire fence fabric supported by the post, or may extend at an angle from the vertical, inwardly or outwardly with respect to the front of the fence fabric, without reversing or changing the position of the said casting; to provide a casting that can be fitted to the post as the fence is being erected without any special machinery; to provide such a device that two arms extending in opposite directions from the vertical may be used upon the same casting; to provide a casting which can be used for a top guard alone to protect the fence post against interior corrosion and to which the arms may be attached at any time; to provide a casting which will furnish a support for the tubular top rail of a fence, which, when fitted to a vertical post, will permit the top rail to deviate from the horizontal to conform to the changing profile of the ground; to provide means for constructing a complete, non-climbable steel fence where effective protection is essential such as athletic fields, estates, parks, prison enclosures, industrial plants, and parking lots.

With these and other objects in view, the invention is illustrated in the attached one-sheet drawing in which Figure 1 is side elevation showing the arm extending outwardly; Fig. 2 is a side elevation showing in dotted lines, the arm in a vertical position, and in full lines the arm extending inwardly; Fig. 3 is a front elevation of Fig. 1, showing in dotted lines two diverse positions of the top

rail; Fig. 4 is a fragmentary perspective view of the arm, and Fig. 5 is a perspective view of a fragmentary section of fence with barbed wire on the steel arms said steel arms extending inwardly.

It is to be understood that the figures in the drawings are illustrative and not restrictive; that other designs and styles of arms may be fitted to the casting; that such details as exact length, size, weight and shape are immaterial.

Like characters of reference designate like parts in all the figures.

In the drawings 1 is a fence post, 2 the adjustable universal post top casting, having base socket 3 which may be made of any size to fit the post 1 being used, the said base 3 and the narrowed mid-section 4 of the said casting 2 forms a complete enclosure for the top of said post 1 and prevents the entrance of dust, moisture or any oxidizing agents which might cause hidden interior corrosion. The narrowed mid-section 4 is provided with an elongated opening 5 surrounded by a thin web 6. Above the said mid-section 4 the top 7 is further narrowed, the junction between the said sections 4 and 7 forming a socket 8 with angular edges, edge 25 extending forward and upward, edge 26 being horizontal and edge 27 extending rearward and upward. The member 7 having a single perforation terminates in an angular point having edges 9 sloping down to conform to the slope taken by the wire supporting adjustable steel arm 10 in both its forward and rearward extending positions. The said arm 10 may have any desired shape but for purposes of this description it has a channel or U-shaped cross-section the attachable end 11 being formed with a perforated bifurcation, the said end 11 slips over and encloses member 7, being held in the desired adjustable position by the bolt 12. For vertical position of the arm 10, the angular edges 15 of the bifurcated end 11 are placed so as to contact with the horizontal edge 26 of the socket 8. For outwardly and inwardly extending positions of the arm 10, the angular edges 14 of the end 11 of arm 10 are placed so as to contact with the said edge 26 of socket 8. When arm 10 extends outwardly as just described,

edge 15 contacts with edge 27, and edge 13 with edge 25. When the arm 10 is reversed and extends inwardly, edge 15 contacts with edge 25 and edge 13 with edge 27. It can thus be seen that the arm is rigidly held in any of these desired positions and that the open side of the U-channel can be turned down and toward the inside. In the illustration the arm 10 is provided with three slits 16 for positioning the wires and three tongues 17 for bending over and holding the said wires but the number of such slits and tongues may be varied to suit any particular purpose. The sides of the arms 10 are made wide and strong at 18 and taper to a narrow, rounded terminus at 19. This method of construction together with the U section provides a light strong support for the wire which will not buckle.

The elongated opening 5 in mid-section 4 is so placed that when top rail 20 is placed therethrough the front of said rail 20 will be in the same vertical plane as the front edge of the post 1, and the front or top face 22 of arm 10 will be in this same plane when the said arm 10, is in its vertical position. The position of the said opening 5 remains the same regardless of the size of base 3 of casting 2 or the size of the post 1 upon which it is placed. The casting 2 remains in the same position on the post regardless of the position and inclination of the arm 10. By reason of the fact that the opening 5 is elongated and is enclosed by the thin web 6, as can best be seen in Fig. 3, considerable inclination can be given to the top rails 20 without striking the base 3 of casting 2 at 23 or edges of mid-section 4 at 24, this will permit the fence to be constructed to conform to the changing profile of the ground. By slightly modifying the bifurcated end 11 of arm 10, two arms extending in diverse directions, may be attached to the same post should this arrangement be desirable. The casting 2 can be used as a final for the post 1, furnishing protection and giving it a neat finished appearance. If later, barbed wire or other wire protection is required the arms 10 and wire may be added as needed. While I have referred to the manner of making my device as a casting it is to be understood that this may be otherwise made such as stamping, and the like.

I have described the preferred embodiment of my invention, but I reserve the right to make such changes in the form, shape, size, weight and other minor changes therein, without departing from the spirit and principle of my invention, or sacrificing any of the advantages thereof.

The preferred embodiment where a top rail is used is as described, but in some instances, such as the leaving off of the top rail, and the like, it may be threaded to fit a similarly threaded portion of a post.

Obviously, the invention is susceptible of

embodiment in forms other than that which is illustrated in the accompanying drawings and described herein, and applicable for uses and purposes other than as detailed, and I therefore consider as my own all such modifications and adaptations and other uses of the form of the device other than as herein described as fairly fall within the scope of my invention.

Having thus described my invention what is claimed and desired to be secured by Letters Patent, is:

1. The top of a fence post of the class described, comprising a top guard for said fence post, having a socket adapted to enclose the top of said post, a first narrowed mid-section thereabove having a central thin web, said thin web having an elongated opening adapted for adjustably positioning a top rail in the same vertical plane of said post, a second upper narrowed section above said first narrowed section having sloping edges adapted to meet a vertical center forming a symmetrical top for said top guard, a wire receiving arm adjustably connecting said second narrowed section adapted for positioning wires in various adjusted positions.

2. The top of a fence post of the class described, comprising a top guard for said fence post, having a socket adapted to enclose the top of said post, a first narrowed mid-section thereabove having a central thin web, said thin web having an elongated opening adapted for adjustably positioning a top rail in the same vertical plane with the face of said post, a second upper narrowed section above said first narrowed section having sloping edges adapted to meet a vertical center forming a symmetrical top for said top guard, a wire receiving arm, said second narrowed section adapted to fit in a plurality of adjusted positions said wire receiving arm.

3. A device of the class described, embodying a socket having a base portion adapted to fit the top of a fence post, and having an integral thin webbed mid-section portion provided with a central elongated opening for receiving the top rail of a fence, said top rail having its face on the same vertical plane as the face of the posts and face of said fence, a second narrow upper integral section above said mid-section having a transverse perforation, a second socket means thereon, and a wire receiving arm adapted for fitting said second socket means in various adjusted positions.

4. A device of the class described, comprising a base socket member adapted to enclose the top of a post, said socket member having its upper mid-section narrowed, said narrowed section containing a central thin web portion, said web portion having therethrough an elongated opening for receiving and positioning a top fence rail, and having a second narrowed upper section thereabove

with a transverse perforation and socket means, said socket means having angular edges, a wire receiving and supporting perforated arm having bifurcated angular edges on one end for co-acting with said angular edges on said socket means, means for holding and positioning said arm in various adjusted positions on said socket means.

5. In a device of the class described, comprising a base socket adapted to enclose the top of a post having its upper mid-section narrowed, said narrowed section containing an elongated perforation encompassed by a thin web, a second narrowed upper section 10 thereabove having a transverse perforation therethrough, a wire receiving arm, means for connecting and positioning said arm in various adjusted positions on said second narrowed section.

15 6. A device of the class described, embodying a base socket member, a mid-section portion, an upper narrow portion and a wire receiving arm, said base socket member adapted for positioning on the upper end of a fence 20 post and the like, said mid-section portion having a thin webbed portion provided with an elongated opening adapted to receive and position the top rail of a fence, said upper narrow portion having socket means, a wire 25 receiving arm, and means for securing said arm in adjusted positions to said last named 30 socket means.
